ALBERT LE ROY WAUGH, OF LOS ANGELES, CALIFORNIA, ASSIGNOR OF ONE-HALF TO REUBEN S. KRAYBILL, OF LOS ANGELES, CALIFORNIA.

MECHANISM FOR PRODUCING RECIPROCATING MOTION.

No. 894,992.

Specification of Letters Patent.

Patented Aug. 4, 1908.

Application filed September 14, 1906. Serial No. 335,499.

To all whom it may concern:

Be it known that I, ALBERT LE ROY WAUGH, of the city of Los Angeles, in the county of Los Angeles and State of California, 5 have invented certain new and useful Mechanism for Producing Reciprocating Motion, of which the following is a full, clear, and exact description or specification, reference being had to the annexed drawings and to 10 the figures and letters marked thereon.

My said invention relates to certain new and useful mechanism.

The mechanism constituting my invention is operated by harnessing one or more horses 15 or by applying other motors to a two armed bar carried upon a vertical shaft or stud in the framing of the machine. This bar is analogous to other bars used in various kinds or types of mechanism driven or operated 20 by a horse or horses walking continuously in a circle.

To the aforesaid bar, when horses are used as the motor is rigidly connected a lever or sweep at right angles or approximately so, 25 and at the under part of the framing whereon the aforesaid two armed bar and lever are carried, there are fixed two curved surfaces which constitute guides, as hereinafter described, upon the inner part of one of which 30 a roller is operated by being pressed upon with one end of the transverse bar during part of a rotation, and which roller is drawn against another part of an inner curved guide surface during another part of a rotation of 35 the mechanism.

To the aforesaid roller a link is connected, and to the outer end of this link a rope or wire cable is connected to the driving pulley which operates the plunger or driver of 40 reciprocating mechanism such as that of a bal- ing press, and which reciprocating mechanism the apparatus constituting my invention is used to impart reciprocating movement to, in the manner hereinafter described.

45 After the driver of the reciprocating mechanism has been driven to the end of its stroke, then the said plunger or driver is drawn backwards by the opposite end of the trans- verse bar attached to the operating lever of 50 the machine coming into contact with an anti-friction roller carried upon a horizontally movable lever, that is to say, a lever movable upon a vertical axis situated upon the framing of the mechanism. To the outer 55 end of this lever a rope or wire cable is at-

tached, the opposite end of which is connect- 60 ed to a second pulley on the axis which carries the aforesaid pulley for operating the driver of the reciprocating mechanism, and the arm of the transverse lever as it is continued in its rotation by the continuous pull of the horses or other motor at the position now referred to, moves the horizontally movable lever inwards, that is to say, towards the center of the framing of the mechanism, thereby 65 drawing the rope or cable so as to pull upon the aforesaid second pulley and thereby rotate the pulley which operates the driver of the reciprocating mechanism in the opposite direction.

Upon the annexed drawings Figure 1, is a 70 plan of the operating mechanism constituting my invention showing a portion of the rod which operates the plunger or driver connected to the pulley which the mechanism constituting my invention operates; this 75 said figure also showing the second and smaller pulley and rope or cable connections whereby the plunger or driver, and driving rod are drawn rearwards after a forward 80 movement of the reciprocating mechanism. Fig. 2, is a side elevation corresponding to Fig. 1.

In these figures of drawings the framing 85 containing and carrying the parts of the mechanism constituting my present invention is marked A, and it consists of strong boards which constitute the floor, and trans-verse beams B, upon which the floor is car-ried and which rest on the ground as shown 90 at Fig. 2, when my new or improved mech-anism is in operation.

When not in operation the machine repre-sented by that part of the drawings consti-tuting my invention, is carried upon wheels 95 placed on the journals C, of the axle D, also strongly attached to the framing or carriage part of my mechanism. To this framing or base a vertical stud or axis E, is rigidly fas-tened. Upon this axis E, the transverse arm 100 F, is mounted, and to the upper part of the transverse arm F, the lever G, is firmly bolted as shown at Fig. 1, this lever G, being the lever to which a horse or a pair of horses is harnessed, and which operates the mech-anism by moving round in a circle, and pulling 105 continuously on the outer end of the lever G, which is shown broken off in Fig. 1, and whereby continuous rotary motion of the said lever G, and the transverse arm F, upon 110

the vertical stud or shaft E, is effected. Upon the framing A, the curved guide H, is bolted, and against the inner curved surface of the guide H, the anti-friction roller I, 5 bears, during that part of its movement from the position whereat it is shown in the drawings up to the opposite end of the guide H. On passing round in the rest of the circle extending from the right hand end of the guide 10 H, the roller I, bears upon the outer surface of a second guide J, until it reaches end of the guide J, from off which it passes into the position shown in dotted lines at K, and is prevented from being pulled rearward by 15 engaging with the catch K', on the arm F. The two circular guides H, and J, respectively, are concentric with each other, and are situated concentrically with the center of the axis of the stud or shaft E. The anti- 20 friction roller I, is forced upwards along the inner face of the circular guide H, by the left-hand end of the transverse arm F, pressing against the anti-friction roller I which is carried upon a vertical stud in the end of the rod 25 L, which is the carrier of the anti-friction roller I, and as this carrier is connected to the rod L, which again is connected by the rope or cable M, to the circumference of a driving pulley N, of a baling press or its 30 equivalent, it is obvious that a continued movement of the roller I, to the righthand end of the curved guide H, pulls the rod L, the rope or cable M, and rotates a pulley N, or other movable part of mechanism, such as a lever or crank to which the 35 cable M, is or may be connected, and in the direction of the arrows shown in Figs. 1 and 2. Since the rod O, which may operate the plunger or driver of a baling press or other 40 mechanism operated by reciprocating mechanism is connected to the pulley N, by means of the crank pin P, it follows that when the roller I, the rod L, the rope or cable M, and the pulley N, are rotated in the direction of the arrows shown in the drawings, the 45 crank pin P, of the pulley N, to which the rod O, is connected is rotated so that the rod O, and the crank pin P, occupy the position opposite to that which they are shown in in 50 the annexed drawings, and that when the rod O, and the crank pin P, are in that opposite position then the plunger or driver has pressed forward the loose hay or other material contained in the receiver of the baling 55 press, and has compressed the loose hay or other material into the bale chamber of said press, or has similarly operated other mechanism actuated by reciprocating motion.

By the time that the driver has been 60 drawn to its utmost inward limit of movement, that is to say, to the bale chamber of the baling press in the manner now last described, or has actuated other mechanism which my apparatus is used to operate as 65 being analogously moved, the transverse

arm F, has reached the position shown by the dotted lines Q, Q, Fig. 1, so that the continuous rotation of the mechanism from the position shown by the said dotted lines Q, Q, causes one end of the transverse arm F, to press upon the roller R, carried at the outer end of the pivoted arm S, which arm S, is centered upon its vertical stud or axis S', firmly secured to the framing of the machine. As this motion of the roller R, continues, the roller R, and lever S, gradually move into the position shown in dotted lines at Fig. 1, at which position the roller R, reaches the opening T, shown at Fig. 2, in the under part of the transverse arm F, and on reaching this position the transverse arm F, continues to move onwards while the roller R, and lever S, are released from being driven further forwards thereby by passing through the opening T. During the movement of the roller R, and the lever S, from the position shown in full lines to the position shown in dotted lines in Fig. 1, the rope or cable T', is pulled in the direction of the arrows shown beneath the rope T', and the outer end of the rope T', being connected to the smaller pulley U, carried upon the axis U', whereon the pulley N, is carried, causes the pulley N, the crank pin P, and rod O, to be pulled out from the baling press, or to similarly operate other reciprocating mechanism to the movable parts of which the rope T', is connected and to be returned into the position shown in full lines in Figs. 1, and 2, which movement being effected, the baling press or other mechanism is ready for the repetition of the operations herein before described. The rope or cable T', in its passage from the roller R, passes around the carrier pulleys a and b, Fig. 1, and in order to keep the said rope T', straight as shown at Fig. 2, the said rope or cable passes partly around the roller U', carried on the stud U' beneath the rope pulley U, as shown in Fig. 2.

For the purpose of preventing a heavy blow or thud taking place at the time when the pulley N, with the rod O, have reached the position shown at Fig. 1, a spiral spring V, is carried upon a stud U', attached to the framing W, of the baling press. This spring V, is so carried by the stud U', as to be situated within the circular slot X, of the pulley N, so that when the crank pin P, and the rod O, have returned to the position shown at Figs. 1, and 2, the end of the slot X, come in contact with the spiral spring V, which receives the blow and pressure caused by the return movement of the pulley N, and the rod O, and thereby a heavy blow or thud is prevented. The wheel Y, represents a portion of one of the carrying wheels of the framing, upon which the framing W, of the baling press is supported.

It is to be understood that while I have herein described and upon the annexed

drawings shown, the mechanism constituting my invention as applied to the operation of a baling press, yet the use of my said invention is not by any means limited to the operating 5 of a baling press exclusively, as the same mechanism in every respect as that which I have herein described and on the annexed drawings shown, may be used for operating a reciprocating rod of any kind for imparting 10 motion to any reciprocating body whether it be the plunger or driver of a baling press, or the plunger or driver of any other machine. I also desire it to be further understood, that that part of the mechanism herein described, 15 and on the annexed drawings shown, consisting of the horizontal shaft carried in bearings, and upon which two pulleys are fastened to the periphery of each of which a rope is connected, which ropes on being al- 20 ternately pulled operate the said shaft and pulleys thereon in opposite directions, need not necessarily be driven by the particular arrangement of rotative horse power mechanism shown upon the annexed drawings, or 25 by equivalent horse power mechanism, and I desire it to be especially understood that the said shaft moving through part of a rotation carrying the said pulleys, also moving through part of a rotation and alternately in 30 opposite directions may be driven by any

machinery adapted for pulling the two ropes alternately.

I claim as my invention.

In mechanism for imparting reciprocating motion, the combination of a centrally piv- 35 oted cross-head, a rod, a roller on one end of said rod, circularly segmental guides for said roller, a rope connected to the opposite end of said rod, a horizontally swinging arm piv- oted at one end, a roller at the opposite end 40 of said arm, a rope connected to said arm, a drum, a pitman secured to said drum, said ropes being attached to said drum so that one of them winds upon the drum as the other one unwinds, all so constructed and 45 arranged that each end of the cross-head when rotated about its pivot will engage successively with and pull upon said rollers whereby a reciprocating motion will be communicated to said pitman, substantially as 50 set forth.

In testimony whereof, I have hereunto set my hand and seal in the city of Los Angeles, aforesaid, in the presence of two subscribing witnesses.

ALBERT LE ROY WAUGH. [L. s.]
